UNITED STATES PATENT OFFICE.

JAMES P. RICHARDSON, OF MANILA, PHILIPPINE ISLANDS.

BASE.

1,158,852.

Specification of Letters Patent.

Patented Nov. 2, 1915.

Application filed February 4, 1915. Serial No. 6,117.

To all whom it may concern:

Be it known that I, JAMES P. RICHARDSON, a citizen of the United States, residing at Manila, in the island of Luzon, Territory of the Philippine Islands, have invented certain new and useful Improvements in Bases; and I do hereby declare the following to be a full, clear, and exact description of the invention, such as will enable others skilled in the art to which it appertains to make and use the same.

This invention relates to improvements in bases for the various types of printing plates and to the method of producing same.

15 The efficiency and commercial value of bases for printing plates depends upon their cost, weight, degree of permanence with which it retains its original form and dimensions, and the ease with which printing plates may be attached thereto. The principal objections to wood bases that are most commonly used is that same will not retain their original form under varying conditions and treatments, warping being the most 25 common change and objection; while bases formed of metal utilized to overcome the change of form prevalent in wood bases are unsatisfactory because of their greater cost, greater weight, and the difficulty experienced 30 in attaching the printing plates thereto.

It is therefore the object of the present invention to provide an improved form of base which combines the advantages and eliminates the disadvantages of the wood 35 and metal bases now in common use.

To this end I provide a base for printing plates whose cost will be at a minimum for the efficiency secured; whose weight, while greater than ordinary wood bases, will be 40 less than that of a metal base; whose permanence of form will be retained under ordinary conditions and treatment; whose composition is such that printing plates may be attached, or mounted, by all methods utilized 45 in attaching printing plates to either wood or metal bases, whose composition is such that it may be machined in any form or manner by either woodworking or metal working machines; and whose composition is such 50 that it may be made any size shape or form for any or all class of product.

A further object of the invention is to provide for making a single base out of a plurality of sections whereby the necessity 55 of having one piece material of the required dimensions is obviated, and further enabling

the base to be constructed by utilizing small pieces of waste material.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a plan view of a base for printing plates constructed in accordance with the invention; Fig. 2, a plan view of the base before the grooves have been filled with metal; Fig. 3, a section on the line 3—3 of Fig. 1; Fig. 4, a section on the line 4—4 of Fig. 1; Fig. 5, a plan view of a modified form of the invention; Fig. 6, a section on the line 6—6 of Fig. 5; Fig. 7, a section on the line 7—7 of Fig. 5; Fig. 8, a plan view of one of the units constituting the base shown in Figs. 5, 6 and 7; Fig. 9, a section on the line 9—9 of Fig. 8, and Fig. 10, a section on the line 10—10 of Fig. 8.

Referring to the drawings and particularly to Figs. 1 to 4 the improved base is shown as comprising a single block of wood A although any other suitable non-metallic material may be employed. One of the major area faces of the block is provided with a plurality of longitudinal grooves 15 and a plurality of transverse grooves 16 said grooves intersecting each other. The other major area face of the block A is provided with a longitudinal groove 17 and a plurality of transverse grooves 18 intersecting the longitudinal groove and being disposed in staggered relation to the transverse grooves 16. The edge faces of the block A are provided with a continuous groove 19 and the grooves 15, 16, 17 and 18 are of sufficient depth to communicate with the groove 19. The grooves 15 and 16 and the grooves 17 and 18 are of sufficient depth to intersect each other at their point of crossing. The grooves 16 and 17 are of sufficient depth to intersect each other at their point of crossing.

From this construction it will be obvious that the various grooves and passages heretofore referred to are in communication with each other. All of the grooves and passages formed in the block A have disposed therein

a filler of suitable metal 23 and as the grooves and passages are in communication with each other it will be obvious that the reinforcement of metal resulting is a continuous integral member having substantially the form of a metal frame work and efficient reinforcement for preventing warping of the block A. The printing plate may be attached to the base thus formed in any desirable manner and when so attached constitutes an additional reinforcement for preventing warping.

In the modified form of the invention shown in Figs. 5 to 10 the block A is constituted by a plurality of similar units B. Each of these units has formed in its major area faces grooves 24 and 25 respectively, said grooves being disposed at right angles to each other and of sufficient depth to intersect at their point of crossing. The edge faces of each unit B have formed therein a continuous groove 26 and the grooves 24 and 25 are of such depth as to communicate with the groove 26. In producing the base from the unit B the latter are cemented together edge to edge with the grooves 24, 25 and 26 of one unit in registration with the corresponding grooves of adjacent units. In this way the block A is formed with grooves in the various faces thereof and with said grooves in communication with each other. The various grooves of the units B are then provided with a filler of metal 27 to form the necessary reinforcing metallic frame. With a base constructed in this manner it will be obvious that small

pieces of waste material can be utilized to advantage without sacrificing the efficiency of the resulting base.

While I have described and illustrated two forms of carrying my invention into practice it will be obvious that various changes in arrangement and details of construction may be resorted to without in any manner departing from the scope of the claims and I therefore desire it to be understood that the invention is in no way limited to the precise forms illustrated and described.

What is claimed is:—

1. A printing plate base comprising a non-metallic body formed of a plurality of independent sections each of which has communicating grooves formed in various faces, the grooves of one section being disposed in registration with corresponding grooves in adjacent sections, and a metallic filling in said grooves.

2. The method of forming printing plate bases consisting of providing a plurality of sections with communicating grooves in various faces, securing said sections together edge to edge with the grooves of one section in registration with corresponding grooves of adjacent sections, and then filling said grooves with metal.

In testimony whereof, I affix my signature, in the presence of two witnesses.

JAMES P. RICHARDSON.
